(57) **CLAIM**

The ornamental design for a barrel cover, as shown and described.

DESCRIPTION

FIG. 1 is a perspective view of a barrel cover, showing the new design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof; and,

FIG. 6 is a bottom plan view thereof.

The broken lines showing a barrel in FIGS. 1 and 5 and a faucet in FIG. 1 are included for the purpose of showing environment, and form no part of the claimed design.

1 Claim, 3 Drawing Sheets

FIG. 1

FIG. 2

FIG. 3

FIG. 4

FIG. 5

FIG. 6
